US0D1016890S

(12) **United States Design Patent** (10) Patent No.: **US D1,016,890 S**
(45) Date of Patent: ** Mar. 5, 2024

(54) **VIDEO CAMERA**(71) Applicant: **Google LLC**, Mountain View, CA (US)(72) Inventors: **Gregory R. Duffy**, San Francisco, CA (US); **Melissa D. McLean**, Novato, CA (US); **Aamir S. Virani**, San Francisco, CA (US)(73) Assignee: **GOOGLE LLC**, Mountain View, CA (US)(**) Term: **15 Years**(21) Appl. No.: **29/758,271**(22) Filed: **Nov. 13, 2020****Related U.S. Application Data**

(63) Continuation of application No. 29/740,737, filed on Jul. 7, 2020, now Pat. No. Des. 905,782, which is a continuation of application No. 29/721,929, filed on Jan. 24, 2020, now Pat. No. Des. 892,195, which is a continuation of application No. 29/656,141, filed on Jul. 10, 2018, now Pat. No. Des. 876,522, which is a continuation of application No. 29/549,992, filed on Dec. 29, 2015, now Pat. No. Des. 826,306, which is a continuation of application No. 14/701,283, filed on Apr. 30, 2015, now Pat. No. 9,871,953, which is a continuation of application No. 13/604,399, filed on Sep. 5, 2012, now Pat. No. 9,071,740.
